UNITED STATES PATENT OFFICE.

BENJAMIN F. SIMPSON, OF ORLAND, CALIFORNIA.

SANITARY WATERING-TROUGH.

1,133,755.

Specification of Letters Patent. Patented Mar. 30, 1915.

Application filed February 25, 1914. Serial No. 820,998.

To all whom it may concern:

Be it known that I, BENJAMIN F. SIMPSON, a citizen of the United States, residing at Orland, in the county of Glenn, State of California, have invented certain new and useful Improvements in Sanitary Watering-Troughs; and I do declare the following to be a clear, full, and exact description of the same, reference being had to the accompanying drawings, and to the characters of reference marked thereon, which form a part of this application.

This invention relates to improvements in watering troughs for use with fowls and small animals and is especially designed as a sanitary watering trough by means of which the same may be kept clean and sanitary in an easy and efficient manner and one which can be readily and quickly disassociated for the purpose of cleansing the same.

A further object of the invention is to produce a simple and inexpensive device and yet one which will be exceedingly effective for the purposes for which it is designed.

These objects, I accomplish by means of such structure and relative arrangement of parts as will fully appear by a perusal of 30 the following specification and claims.

In the drawings similar characters of reference indicate corresponding parts in the several views.

Figure 1 is a side elevation of the complete trough. Fig. 2 is an end view of the same. Fig. 3 is a sectional view taken on a line X—X of Fig. 2. Fig. 4 is a sectional view of a disinfectant carrying tube adapted to be mounted on the sides of the trough. 40 Fig. 5 is a sectional view of the tube taken on a line relatively Y—Y of Fig. 4.

Referring now more particularly to the characters of reference on the drawings I first provide a supporting standard comprising two end members 1 each having an upper bifurcated end 2 to act as journal seats for bearings for the trough as will presently appear. The members 1 are provided with suitable supporting feet 3 joined by a cross brace 4. The trough structure comprises a lower trough 5 and an upper inverted trough 6. The member 5 is secured at each end to the end board 7 and the member 6 is likewise secured at each end to the end board 8. Each end board 7 and 8 is provided at each end with one half of a journal

pin 9 and 10 respectively, which, when the end boards 7 and 8 are disposed adjacent to each other form complete bearing pins which fit into the bifurcated bearings 2 60 which form seats for such pins 9—10. Each of the halves 9 and 10 is provided with a projecting flange 11 and 12 respectively on its outer end to project over and against the outside of the member 1 to hold the pins 65 9—10 from any end play in their seats. These flanges 10 and 11 each have projecting lugs 13 and 14 respectively fitted into corresponding recesses in the adjacent flange in order to lock the same together against 70 any lateral play so that when the pins 9—10 revolve the entire structure comprised of the troughs and the end boards will revolve as a unit. As will be noted then, the trough structure comprises an upper and a lower 75 trough removably joined but locked together so that they may rotate as a unit whereby the lower trough may be inverted to become the upper trough and the upper trough may be righted to become the lower 80 trough so that the use of the troughs may be alternated whereby they will not become foul and unsanitary. Also by reason of the independent members 6 and 7 and the independent bearings the upper trough may be 85 entirely removed from the lower trough for the purpose of cleansing or repairing the same. In addition to this sanitary structure just described, I provide a means for disinfecting the heads of the fowls whenever they come to use the troughs which disinfectant 90 means comprises a tube 15 open at one end and provided with a cork 16 which tube is split along its length its split ends overlapping as at 17, there being a wick 18 inserted between the overlapping portions and projecting from the inside to the outside of the tube 15. Such tube 15 may then be filled with any suitable disinfectant material and hung along side of the troughs by means 95 of rings 19 engaging hooks 20. The disinfectant material will then saturate the wick 18 and hence when the fowls use the trough their heads will come in contact with the wick 18 and receive a portion of the disinfectant material thus automatically keeping 100 them free from infection.

From the foregoing description it will be readily seen that I have produced such a device as substantially fulfills the object of the invention as set forth herein.

While this specification sets forth in de-

tail the present and preferred construction of the device, still in practice such deviations from such detail may be resorted to as do not form a departure from the spirit 5 of the invention.

Having thus described my invention what I claim as new and useful and desire to secure by Letters Patent is:—

1. A device of the character described 10 comprising a supporting standard consisting of end members provided with bifurcated seats at their upper ends, two pair of end boards, each board having a semi-circular journal pin, such semi-circular journal pins 15 on adjacent boards lying adjacent each other to form a complete circular pin, such pins resting on said bifurcated seats, means on said pins for holding them in position on said seats and a trough carried by each pair 20 of boards, as described.

2. A device of the character described comprising supporting members each hav-

ing a seat at its upper end, two pair of end boards, each board having a semi-circular pin, said semi-circular pins lying adjacent 25 to each other to form complete circular pins, such pins resting in said seats, each part of each of said pins having a projecting flange on its outer end and a trough carried by each end board, as described.

3. A device of the character described 30 comprising end boards each formed of two removable halves, journal pins on said halves, means providing seats for said journal pins to permit said end boards to revolve 35 as a unit, means on said pins for securing them in said seats, and a trough carried by each of said end boards, as described.

In testimony whereof I affix my signature in presence of two witnesses.

BENJAMIN F. SIMPSON.
